UNITED STATES PATENT OFFICE.

GEORGE E. BISHOP, OF CLEVELAND, OHIO.

AUTOMOBILE INCLOSURE.

1,425,444.

Specification of Letters Patent. Patented Aug. 8, 1922.

Application filed July 22, 1920. Serial No. 398,138.

To all whom it may concern:

Be it known that I, GEORGE E. BISHOP, a citizen of the United States, resident of Cleveland, county of Cuyahoga, and State of Ohio, have invented new and useful Improvements in Automobile Inclosures, of which the following is a specification, the principle of the invention being herein explained and the best mode in which I have 10 contemplated applying that principle, so as to distinguish it from other inventions.

My invention relates to automobile inclosures, and particularly to the upper door-section of such inclosures. More particularly, the invention relates to a new and improved frame for an upper door-section which is adapted to carry a glass outlook, although an adaptation is very suitable for a celluloid outlook.

20 The annexed drawings and the following description set forth in detail certain means embodying my invention, the disclosed means, however, constituting but a few of the various mechanical forms in which the principle of the invention may be applied.

In said annexed drawings:—

Figure 1 represents an inside view of one form of my invention, in which the glass 30 outlook is supported in a frame carried in the fabric curtain, together with other details of construction which will hereinafter more fully appear;

Figure 2 represents a transverse horizontal section, upon an enlarged scale, taken in the planes indicated by the line II—II, Figure 1;

Figure 3 represents a transverse, vertical section, upon an enlarged scale, taken in the plane indicated by the line III—III, Figure 1;

Figure 4 represents a broken, transverse, vertical section, taken in the planes indicated by the line IV—IV, Figure 1;

Figure 5 represents an elevation of one of the supporting rods utilized in the construction shown in Figure 1;

Figure 6 represents an inside view of another type of inclosure, in which the glass outlook is supported in a combination wood and sheet metal frame, disposed adjacently to the edges of the fabric, together with other modifications in the supporting rod, etc., which will hereinafter more fully appear;

Figure 7 represents a transverse, horizon-

tal section, taken in the plane indicated by the line VII—VII, Figure 6;

Figure 8 represents a transverse, horizontal section, upon an enlarged scale, taken in the plane indicated by the line VIII—VIII, Figure 6;

Figure 9 represents a transverse, vertical section, taken in the plane indicated by the line IX—IX, Figure 6;

Figure 10 represents a transverse, vertical section, upon an enlarged scale, taken in the plane indicated by the line X—X, Figure 6;

Figure 11 represents an elevation of one of the supporting rods utilized in connection with the inclosure shown in Figure 6;

Figure 12 represents a fragmentary, vertical, longitudinal section of certain portions of the inclosure shown in Figure 6;

Figure 13 represents an inside view of a third type of inclosure, in which the supporting rod, wood frame members, and some other details are modified somewhat from the form shown in Figure 6;

Figure 14 represents a transverse, horizontal section, taken in the plane indicated by the line XIV—XIV, Figure 13;

Figure 15 represents a transverse, horizontal section, upon an enlarged scale, taken in the plane indicated by the line XV—XV, Figure 13;

Figure 16 represents a transverse, vertical section, taken in the plane indicated by the line XVI—XVI, Figure 13;

Figure 17 represents a transverse, vertical section, upon an enlarged scale, taken in the plane indicated by the line XVII—XVII, Figure 13; and

Figure 18 represents an elevation of one of the rods used in connection with the curtain shown in Figure 13.

Referring to the annexed drawings, and particularly to Figures 1 to 5 inclusive, there is therein disclosed an automobile side inclosure adapted to constitute an upper door section. Said section carries a glass outlook 6, is adapted to be supported upon the door 1 by rods 9 and 10, as will hereinafter more fully appear in detail, and to ride in and out upon the door as the latter is opened and shut along the hinge line indicated by the ordinal 2. Sections of the automobile body contiguous to the door 1, are indicated by the ordinals 3 and 4, respectively. This upper door section of the automobile inclosure is supported upon $\frac{3}{8}$ " cylindrical rods 110

- 9 and 10, whose lower ends are supported in cylindrical metal bushings 17 positioned in suitable recesses 18 formed in the top of the door 1.
- 5 The curtain fabric is indicated by the ordinal 5, and a section of the same, 5', is disposed between an outer metal curtain frame proper and an inner auxiliary frame which will hereinafter be described in detail, and within which the glass outlook 6 is supported. The outer metal supporting frame consists, in combination with the vertically disposed rods 9 and 10, of a horizontal lower rectangular section 7 with an upturned angular end 7' terminating substantially at the point 7²; and a horizontal, upper, rectangular section 8; said sections 7 and 8 being comprised of flat steel bars approximately $3\frac{3}{8}$ " thick, and being incorporated within the fabric 5. The supporting cylindrical rods 9 and 10 are formed with rectangular upper sections 9' and 10', substantially $\frac{1}{8}'' \times \frac{1}{8}$ ", which are positioned in slots 15 and 16 formed in the respective side edges of the fabric 5, the rod 9 being fastened to the section 7 and the section 8 by the rivets 11 and 12, respectively, and the rod 10 being fastened to said sections 7 and 8 by the rivets 13 and 14, respectively. It has already been noted that the lower ends of the rods 9 and 10 are mounted in cylindrical bushings 17 contained within the door recesses 18. The rods 9 and 10 are formed with the offsets 9² and 10², plainly shown in Figures 1, 4 and 5, whereby the frame can be provided with overlapping side edges which are efficiently supported and strengthened and at the same time the frame is supported upon the door 1 and overlaps the top of the latter. The frame formed by the members 7, 8, 9 and 10; in combination with the elements 17, removably supports the inclosure upon the door 1 so that the same can ride in and out with the door, the recesses 18 being formed adjacently the outer edge of the door, Figure 4, so that the offsets 9² and 10² are not deep enough materially to increase the thickness of the inclosure when the same is stored.
- 50 The outlook 6 is supported in a substantially rectangular frame consisting of $\frac{3}{8}'' \times \frac{1}{8}$ " wood members 20, to the outer faces and outer lateral edges of which are secured sheet metal strips 21, made from stock substantially 26 gauge. The fabric 5 is wrapped about the metal frame members 7, 8, 9, 10 and the combination wood and metal frame 20-21, commencing at the corner 22 of the frame 20, Figure 2, thence running outwardly along the inner edge of the frame member 20 and around an inner extending nose portion 21' of the sheet metal member 21, thence across the outer face of the sheet metal member 21 and transversely, as the intermediate fabric section 5', over and beyond the members 7, 8, 9, and 10, to form the lapping edge of the curtain where the fabric is supported by a wire netting 19—except at the upper edge—thence over the inner side of said netting 19 and over the inner sides of the sections 7, 8, 9, and 10, completing a double thickness of the fabric section 5', and thence over the inner sides of the frame member 20 to the corner 23, Figure 2. The actual process of thus disposing the fabric 5 consists preferably in working inwardly from the point 53 with upper and lower sections of fabric which are stitched together at this point. The ends 22 and 23 of the fabric are secured by tacks 24 driven into the frame members 20. The fabric 5 adjacently the inner edges of the netting 19 is stitched through said netting. Also, it is stitched adjacently the upper edge of the metal frame member 8 to form the upper lapping edge 5², Figures 3 and 4. The outlook 6 is then laid upon the fabric, which is supported by the nose portions 21' of the sheet metal members 21, and molding strips 25 secured interiorly of the outlook 6 by means of tacks 26 driven through said molding and in the wood frame members 20. Suitable other tacks, as desired, are utilized for adequately securing together the several elements. In the event it is desired to use a celluloid outlook instead of the glass outlook, I dispense with the combination metal-wood inner frame and utilize only the outer metal supporting frame consisting of the rods 9 and 10 and bars 7 and 8.
- In the type of inclosure shown in Figures 6 to 12 inclusive, ordinals 1, 2, 3, 4, 5, 6, 25 and 26 refer to details similar to those shown in Figures 1 to 5. In the type of inclosure shown in Figures 6 to 12, there is no intermediate fabric section, similar to the section 5' shown in Figure 1, but the glass outlook 6 is supported in a combination sheet metal and wood frame member disposed adjacently the edges of the inclosure. In these figures, the frame consists of wood members 27 and sheet metal members 29, between the side members of which the supporting rods 37 are positioned, as hereinafter particularly described. In this construction, the sheet metal member 29 is secured to the outside faces of the wood frame sections 27 by tacks 30, and extends from the point 28 interiorly of the wood member 27, Figure 8, to the outer edge of the supporting rods 37, on the sides or to the inner faces of the top and bottom, respectively, of the horizontal frame members 27, Figure 10, and thence on the sides around the rods 37, to the point 28', Figure 8; the nose 29' thus forming a supporting flange for the glass outlook 6 similar to the construction shown in Figure 1. In this construction, the fabric 5 commences at the corner 31' of the frame member 27, Figure 8, runs across the inner edge

of said member 27, thence around the nose 29', member 29, netting 19, and thence to the corner 34 of the frame member 27. The fabric 5 is secured by the tacks 35 driven into the frame members 27. Similarly to the construction shown in Figures 1 to 5, the glass outlook 6 is supported upon the fabric 5, intermediately the nose 29' of the sheet metal supporting member and the molding 25. It will be seen that this construction provides an opening 40, Figure 8, bounded by the wood members 27, and the sheet metal members 29, within which the supporting rods 37 are positioned. These rods 37 are 10 formed with rectangular supporting ends 38, Figure 11, adapted to be received by brackets 39 having openings rectangular in cross section and secured to the inner face of the door 1. These brackets 39, of which an elevation plainly appears in Figure 6, are of the design forming the subject matter of my companion application for Design Letters Patent of the United States, Serial No. 345,139. The sheet metal of the frame is 15 assembled from several sections, and the overlapping edges of the different sections at the corners are indicated by the ordinal 41, Figure 6. The several sections are of a size and contour, and the overlapping edges 20 are located in positions, all governed by the size and shape of the particular outlook 6 which happens to be utilized. In this form of construction, it is evident that, when the end portions 38 of the rods 37 are 25 removed from the brackets 39, these supporting ends 38 can be turned down, relatively to the fabric and outlook and connected parts, so as to enable the frame as a whole to be stored flat and in a very small 30 space. This last-named feature is similar in result to the function accomplished by a double swivel in the type of inclosure shown, described and claimed in my companion application for U. S. Letters Patent, Serial 35 No. 327,952.

Referring to the type of upper door-inclosure shown in Figures 13 to 18, the same differs from the type shown in Figures 6 to 12 in that the lower portion 43, Figure 50 18, of the supporting rods are cylindrical and the upper portions 44 are rectangular in cross-section, said sections 43 and 44 being preferably welded together at the point 45. The rectangular upper sections 44, which 55 are of comparatively small cross-sectional area, are contained within suitable pockets or recesses 46, formed in the wood frame members 42. The fabric is stretched from the point 31', inside member 42, Figure 15, 60 around members 29', 29, 29² to point 32. The member 29² is a sheet metal insert which is substituted for the netting 19, if desired. The netting 19, Figures 1 to 6, is simply a 65 reinforcing wing which is resilient and keeps the fabric 5 from wearing when the fabric

contacts with wood or metal; however, when the fabric 5 does not contact with wood or metal, the metal inserts 29² are used, Figures 13 to 18. It will be noted, Figure 13, that these metal inserts 29² form a U-shaped frame and the several members of the frame are pivotally connected together at the connecting points 51 and 52 so as to form a U-frame which can buckle or tend to close up in action. This pivotal connection at the points 70 51 and 52 is obtained by punching a hole through one of the inserts 29² and punching another insert 29² so that the material thereof is laterally extended into a broken generally conical protuberance which is inserted 75 through the hole of the first-mentioned insert and then the outer edge of the protuberance upset to produce a secure connection which, however, allows for the relative pivotal movement of the two members. The 80 possible buckling action of the U-shaped frame 29² is serviceable in assembling when it is necessary to buckle the two legs of the frame in order to insert the latter into the fabric covering. Between points 33 and 34, 85 90 upon the inner and outer edges, respectively, of member 42, is stretched a lining 36, if desired; or fabric 5 may be utilized between these points. The fabric 5 and lining 36 are secured by tacks 35 driven into members 95 42. It is not necessary in this form of enclosure to provide an angular outer extension of the metal member 29, forming a recess to receive the supporting rod, because the section 44 of the rod is thin compared 100 with the wood member 42, and is disposed within said wood member, so that the metal member 29 is terminated adjacently the outer edge of the wood member 42, thus completing 105 a rectangular wood and metal pocket 46 for rod 44. In this construction, it is evident that the supporting rods cannot be turned down, with reference to the rest of the frame, when the frame has been removed from the door, for the purpose of storing in small 110 space, so that, in order to obviate the frame taking up too much space for storage, I have formed the sockets 18, which are in the upper edge of the door, adjacently the outer face of the door, for taking the bushings 17 115 and the supporting ends of the rods 43, as plainly appears in Figure 14. This is similar to the construction shown in Figures 1 to 5. As before explained, by this construction, the offset 47, Figures 14 and 16, is so slight that there is no necessity for turning down the rod 43 for storage purposes. The comparative sizes of the upper and lower wood frame members 48 and 50, Figure 13, 120 relative to the side frame members 42, are substantially shown in Figures 15, 16 and 17, Figure 16 being substantially one-fourth the scale of Figures 15 and 17. The method of mounting the glass outlook 6 inside the combination wood and sheet metal frame is 125 130

similar to that shown in Figures 6 to 12. The overlapping corners of the several members forming the sheet metal frame are indicated by the ordinals 49, Figure 13. The 5 several frame members which I show for purposes of illustration only are so cut as to allow for the particular design of glass outlook 6 which is shown in the drawing.

The types of upper door inclosures which 10 I have above described, and which are shown in the accompanying drawings and herein-after claimed, are efficient in service, are rigid, except for the potential buckling of the form shown in Figure 13, as well as being 15 very light and thin.

In the form of curtain shown in Figure 13, the sheet metal inserts 29² are provided upon the two sides and the top of the inclosure and are pivotally riveted together 20 at the top corners, whereby the frame is reinforced on all three sides.

What I claim is:

1. The combination, in an enclosed vehicle having an entrance and a door for the 25 lower part of said entrance, of a construction of the upper door-section of the inclosure consisting of, a glass outlook; a wooden frame bounding said outlook; sheet metal strengthening members covering one 30 face of said frame and extending interiorly thereof to form a rest for one side of said outlook; means retaining said outlook against said rest; suitable fabric covering said frame and sheet metal members and 35 exteriorly overlapping the same; and rods for removably mounting the inclosure upon the vehicle door.

2. The combination, in an enclosed vehicle having an entrance and a door for the 40 lower part of said entrance, of a construction of the upper door-section of the inclosure consisting of, a glass outlook; a wooden frame bounding said outlook; sheet metal strengthening members secured to 45 said frame and extending interiorly thereof to form a rest for one side of said outlook; means retaining said outlook against said rest; suitable fabric covering said frame and sheet metal members and 50 exteriorly overlapping the same; metal inserts, in combination with said overlapping fabric, forming sealing inclosure edges; and rods for removably mounting the inclosure upon the vehicle door.

55 3. The combination, in an enclosed vehicle having an entrance and a door for the lower part of said entrance, of a construction of the upper door-section of the inclosure consisting of, a glass outlook; a 60 wooden frame bounding said outlook; sheet metal strengthening members secured to the outer face of said frame; spaced means secured interiorly of said frame adjacently the inner and outer faces thereof and forming 65 rests for said outlook, the latter being

disposed intermediately the resting means; rods, for removably mounting the inclosure upon the vehicle door, incorporated within said wooden frame and strengthening members; and suitable fabric covering said frame and sheet metal members and exteriorly overlapping the same. 70

4. The combination, in an enclosed vehicle having an entrance and a door for the lower part of said entrance, of a construction of the upper door-section of the inclosure consisting of, a glass outlook; a wooden frame bounding said outlook; sheet metal strengthening members secured to 75 said frame and extending laterally thereof and forming a channel adjacent the edge of said frame; spaced means secured interiorly of said frame adjacently the inner and outer faces thereof and forming rests for said outlook, the latter being disposed 80 intermediately the resting means; rods, for removably mounting the inclosure upon the vehicle door, incorporated within said channel; and suitable fabric covering said frame and sheet metal members and exteriorly 85 overlapping the same. 90

5. The combination, in an enclosed vehicle having an entrance and a door for the lower part of said entrance, of a construction of the upper door-section of the inclosure consisting of, a glass outlook; a wooden frame bounding said outlook; sheet metal strengthening members secured to the outer face of said frame, extending exteriorly thereof and forming a channel adjacent the outer edge of said frame, said sheet metal members also extending interiorly of said frame to form a rest for the outside of said outlook; a bead secured interiorly of said frame, and adjacently the inner face thereof for retaining said outlook; rods, for removably mounting the inclosure upon the vehicle door, incorporated within said channel; and suitable fabric covering said frame and sheet metal members and exteriorly overlapping the same. 95 100

6. The combination, in an enclosed vehicle having an entrance and a door for the lower part of said entrance, of a construction of the upper door-section of the inclosure consisting of, a glass outlook; a wooden frame bounding said outlook; sheet metal strengthening members secured to the outer face of said frame and extending interiorly thereof to form a rest for the outside of said outlook; a bead secured interiorly of said frame and adjacently the inner face thereof for retaining said outlook; square rods, for removably mounting the inclosure upon the vehicle door, disposed within pockets formed by said wooden frame and said strengthening members, said rods having cylindrical lower ends and the door having vertical cylindrical recesses adjacently its outer face for receiving 115 120 125 130

ing said rod ends; and suitable fabric covering said frame and sheet metal members and exteriorly overlapping the same.

7. The combination, in an enclosed vehicle having an entrance and a door for the lower part of said entrance, of a construction of the upper door-section of the inclosure consisting of, an outlook; an outer supporting frame comprising upper and lower horizontal bars and vertical side bars rigidly secured to said horizontal bars; suitable fabric within which the outlook is supported, said fabric extending outwardly from said outlook, then covering said frame, and exteriorly overlapping the latter; metal inserts, in combination with said overlapping fabric, forming sealing inclosure edges; and means for removably mounting the inclosure upon the vehicle door.
- 20 8. The combination, in an enclosed vehicle having an entrance and a door for the lower part of said entrance, of a construction of the upper door-section of the inclosure consisting of, a glass outlook; a wooden frame bounding said outlook; spaced means secured interiorly of said frame adjacently the inner and outer faces thereof and forming rests for said outlook, the latter being disposed intermediately the 25 resting means; suitable fabric covering said

frame and exteriorly overlapping the same; a three-sided frame incorporated within said overlapping fabric and comprised of sheet metal members pivotally riveted together; and rods for removably mounting 35 the inclosure upon the vehicle door.

9. The combination, in an enclosed vehicle having an entrance and a door for the lower part of said entrance, of a construction of the upper door-section of the inclosure consisting of, a glass outlook; a wooden frame bounding said outlook; sheet metal strengthening members secured to said frame; spaced means secured interiorly 40 of said frame adjacently the inner and outer faces thereof and forming rests for said outlook, the latter being disposed intermediately the resting means; suitable fabric covering said frame and sheet metal members and exteriorly overlapping the 45 same; a three-sided frame incorporated within said overlapping fabric and comprised of sheet metal members pivotally riveted together; and rods, for removably mounting the inclosure upon the vehicle door, incorporated within said wooden frame and 50 strengthening members.

Signed by me this 16" day of July, 1920.

GEORGE E. BISHOP.
